UNITED STATES PATENT OFFICE

2,006,777

WOOD PRESERVING APPARATUS

Grant B. Shipley, Pittsburgh, Pa.

Application November 13, 1933, Serial No. 697,784

5 Claims. (Cl. 99—12)

The invention relates to wood-treating apparatus such as is used for impregnating wood with preservative solutions. Wood-treating plants in use today are generally complicated structures made up of a variety of tanks, pressure and vacuum pumps, numerous lengthy pipe lines, and other elements. Consequently, such plants are large and expensive, with much to get out of order and to keep 10 in repair, and each requires several skilled men to operate it. It can thus be seen that many industries which would like to use wood-treating plants are prevented from doing so by their size and excessive cost. Also, it has not been feasible 15 or economical to install such equipment for field operations.

It is among the objects of this invention to provide a wood-treating plant of comparatively simple, inexpensive and compact construction, 20 which uses a minimum number of elements, which can be operated by the average workman without confusion or assistance, may be erected and operated at substantially any desired point and is particularly adapted for field operation, is 25 efficient and economical to operate, and utilizes steam in its operation, whereby the customary pumps, condensers and the like heretofore necessary are dispensed with.

The invention may be described in connection 30 with the accompanying diagrammatic drawing, of which Fig. 1 is a side view of one embodiment; Fig. 2 a plan view of the treating cylinder and its connections, taken on line II—II of Fig. 1, and Fig. 3 a modified form of pressure measuring 35 tank.

Referring to Figs. 1 and 2 of the drawing, the embodiment shown includes a horizontally disposed wood-treating cylinder 1, having a conventional sealing door 2 at one end, and it may 40 be mounted on a suitable foundation, not shown. Disposed above the treating cylinder is a large tank divided into two smaller tanks 3 and 4 by a transverse wall 5. The right-hand tank 4 is a combined storage, working and Rueping tank 45 containing a wood preservative solution, such as creosote, solution of zinc chloride, or Wolman salts, or the like. The left-hand tank 3 is a pressure measuring tank containing additional preservative solution on which pressure is exerted to force preservative into the wood being 50 treated in the treating cylinder, with which tank 3 can be put into communication.

Although the storage and pressure measuring tanks need not necessarily be joined, combining 55 them in one large cylinder in the above manner saves space, makes the apparatus more compact, and reduces expense since wall 5 serves as an end wall for two tanks. The large double-tank cylinder and the treating cylinder are, therefore, 60 the only large pieces of equipment used in this

embodiment of the invention; the rest of the elements consisting of pipes, valves and an ejector which are shown diagrammatically in the drawing. With only the two cylinders to be interconnected, it will be seen that the connecting pipe lines are relatively short and simple. 5

A particular feature of the invention resides in the use of fluid pressure for applying impregnating pressure and vacuum, thereby rendering unnecessary the multiplicity of pumps and associated equipment heretofore needed with such apparatus. This further simplifies and cheapens the apparatus, as may be understood better from the following detailed description of the embodiment shown in Figs. 1 and 2. 10

Referring in particular to the piping, a conduit 11 connects the bottom of storage tank 4 to the bottom of treating cylinder 1 for conducting preservative solution by gravity to the treating cylinder and for returning preservative to the storage tank, and a branch 12 connects conduit 11 to a drain line 13 which empties to any suitable point, e. g., a sump. Conduit 11 is of sufficient size to permit rapid filling and emptying of the treating cylinder. The bottom of pressure measuring tank 3 is connected to the bottom of the treating cylinder by a conduit 14 through, for example, a conduit 16 connected at one end to branch 12 and at the other end to a manifold 17. A branch 18 (Fig. 2) connects conduit 16 20 also to a pipe 19 which is connected at its upper end to the top of pressure measuring tank 3 and at its lower end to a conduit 21 the lower end of which acts as a blow-off line and opens into a sump, for example. The upper end of conduit 21 is in communication with the top of storage tank 4, and an upper branch 22 connects it to the manifold. Between this branch and the juncture with conduit 19 is a short branch 23 from which a conduit 24 leads to manifold 17. Another conduit 26 extends from the short branch 23 to the top of the pressure measuring tank, and still another conduit 27 extends downward from branch 23 and opens into a funnel 28 connected to the upper end of drain pipe 13. A conduit 29 (Fig. 2) connects conduit 24 to the top of the treating cylinder. 25

It will be observed that there are several other pipes leading to and from manifold 17. One of these 31, connected to the end of manifold 17 30 leads from a source of fluid pressure, such as air or steam, and conduits 32 and 33 between supply conduit 31 and conduit 22 lead to heating coils in the pressure measuring and storage tanks for heating the wood preservative which they contain. Conduit 34 leads from the bottom of the manifold 35 and is connected to a heating coil in the treating cylinder, and conduit 36 leads to a perforated coil in the treating cylinder through which steam is introduced for steaming green wood to open its 40 45 50 55 60 65 70 75 80 85 90 95

cells for the reception of the preservative. As all of these coils are of well known form, they and the connections thereto are not shown in the drawing.

5 A conduit 31 is connected to a mixing pit, not shown, suitably adjacent the apparatus, in which the preserving solution may be prepared before admission to the storage tank. Conduit 38 is connected to the pressure inlet of an ejector 39 whose suction side is connected by a conduit 42 to the top of the treating cylinder. Conduit 41, connected to manifold 17, acts as a drain pipe. The outlet of the ejector is connected by a conduit 43 to a waste conduit 44 having a depending portion through which condensate drains.

10 In operating this wood-treating apparatus, loads of wood to be treated are run on tram cars into treating cylinder 1, whereupon door 2 is tightly closed. A valve 50, next to manifold 17, in pipe 16 is now opened to connect the source 20 of fluid pressure, in line 31, preferably steam, to the top of the pressure measuring tank through the manifold and conduits 16, 18 and 19, valve 51 in pipe 18 being closed at this time. Valve 25 52 in pipe 11 is then opened to permit the preserving solution in storage tank 4 to flow by gravity into and fill the treating cylinder.

30 After the cylinder has been filled, valve 52 is closed and a valve 53 in pipe 14 is opened, thereby establishing communication between the bottom of the pressure measuring tank and the bottom of the treating cylinder through pipes 14, 16, 12 and 11. Valve 54, in pipe 16 between pipes 18 and 14, is closed during this stage to keep the pressure 35 fluid from entering the bottom of tank 3. The fluid pressure applied to the top of the pressure measuring tank acts through the preservative solution therein to force the preservative in the treating cylinder into the cells of the wood being 40 treated.

45 The pressure is regulated to meet the requirements of the particular kind of wood being treated. Green wood may first be steamed in the treating cylinder to open its cells, the steam being admitted by opening valve 56 in pipe 38 leading from the manifold to the cylinder. If the high pressure fluid used in operating the plant is not steam, steam can be obtained from any other 50 convenient source for the wood-steaming step and connected into supply pipe 31 by a suitable valve.

55 After the wood has been thoroughly impregnated by the preservative, which is held under pressure by the fluid pressure fluid in tank 3, the pressure supply is shut off before it reaches the manifold, and valve 53 in pipe 14 is closed. Valve 52 is then opened to again establish communication between the bottoms of the storage tank and the treating cylinder, and valve 57 in pipe 24 is opened, valve 58 therein being closed. 60 This permits the excess pressure fluid in the top of the pressure measuring tank to expand and enter the top of the treating cylinder through pipes 19 and 16, manifold 17, and pipes 24 and 29, thereby forcing the preservative solution from 65 the treating cylinder through pipe 11 and back into storage tank 4.

70 If more solution is blown back than the storage tank can hold, it will overflow through pipes 21, 23 and 27 and start flowing into drain pipe 13, valve 61 in pipe 21 below pipe 23 being closed. When it is seen to flow from the lower end of pipe 27 into funnel 28, valve 50 is closed to stop the blow back, and valve 51 is opened to permit the remaining pressure in tank 3 to escape through 75 the outlet of pipe 21. Valve 62 in pipe 27 is

then closed, and valve 63 in pipe 26 is opened to open an overflow conduit between tanks 3 and 4. Fluid under pressure is again admitted to the manifold through pipe 31, the fluid entering the top of the treating cylinder through pipes 24 and 29 to blow the remainder of the solution back into the storage tank from which it overflows into the pressure measuring tank.

5 For the purpose of relieving pressure in the treating cylinder when that is desired, a conduit 10 68 is connected to its top and to a pressure outlet pipe 69 suitably disposed beside vertical outlet pipe 44. Conduit 68 is controlled by a valve 70 therein.

Conduit 22, connecting manifold 17 to conduit 15 21, permits fluid pressure to be applied to the top of storage tank 4.

20 In order to withdraw the excess amount of preservative from the treated wood to prevent drippage and waste, a vacuum is applied to the treating cylinder by closing valves 57 and 52 and opening valve 65 in pipe 38 to permit the high pressure fluid to pass through ejector 39 and pipe 43 to the vertical outlet pipe 44, the rush of fluid through the ejector creating a vacuum in the cylinder. The excess preservative escaping from the treated wood is drained from the cylinder by opening valve 66 in pipe 12.

25 The pressure measuring tank, as its name indicates, is both a pressure and a measuring tank. 30 The amount of preservative absorbed by the treated wood is indicated by a volume gauge 67 of any suitable design in communication with the preservative in tank 3. The gauge is read directly after valve 53 is opened to connect the pressure 35 measuring tank with the treating cylinder, and again after the final blow-off and overflow from the storage tank. The difference in readings indicates the amount of preservative used.

40 Although it is preferred to operate the apparatus solely by steam, as just described, the impregnating pressure may be obtained by and the ejector operated with compressed air. In such a case, if the air pressure available is not sufficiently great to afford the necessary pressure, it may 45 be desirable to connect a combined compressor and vacuum pump to supply-pipe 31 in order to increase the incoming air pressure if necessary, or to hold the vacuum in the treating cylinder after its air has been initially exhausted by the 50 ejector. For the latter purpose the pump may be connected to outlet pipe 43 of the ejector.

55 However, it is more advantageous to operate the apparatus by steam pressure, because steam is usually available, e. g., for use in heating the 60 preservative, as in the tanks and cylinder. If steam is not so readily available, it can be supplied by a small high-pressure steam boiler. In any event, the use of steam is highly advantageous, because it is capable of performing the various duties heretofore performed by pumps, compressors and the like, such as forcing the preservative solution from one tank to another, creating pressure in the tanks, and creating a vacuum in the treating tank or cylinder. For this purpose a steam pressure of anywhere from 100 65 to 250 pounds, or a superheated steam at those pressures, is sufficient.

70 Due to the area of preservative exposed to the pressure fluid in the pressure measuring tank and also due to the depth of the solution therein, difficulties may be experienced both from a high rate of steam condensation and also from strain on the tank due to differences in temperature of the preservative and tank between the upper and 75

lower portions which induces differential expansion and consequent strain on the tank. A form of pressure measuring tank which minimizes these difficulties and can be used in place of tank 5 3 is shown in Fig. 3. It consists of a plurality of vertically disposed cylindrical tanks 81 of relatively small cross-sectional area, such as large diameter pipe, the combined capacities of the tanks being substantially equal to the capacity of 10 tank 3.

These small tanks are connected in series, i. e., the bottom of one to the top of the other. Most suitably they are arranged in staggered relation with the bottom of the first tank connected by 15 pipe 86 to the top of the second tank whose bottom is connected by pipe 87 to the top of the third tank, and so on along the line. Pressure-supplying pipe 19 is connected to a pipe 88 which extends along the line of small tanks. A short 20 pipe 89 leads from pipe 88 to the top of the first tank to apply fluid pressure to the preserving solution contained therein. As the volume of the first tank is very much less than that of tank 3, the rate and amount of steam condensation there- 25 in is also less. To prevent this volume from becoming any greater than that of one small tank as the preserving solution is used up in impregnating wood, means is provided for cutting emptied tanks out of the line.

30 This means consists of branch pipes 91, 92 and 93 which lead from pipe 88 to each respective pair of tank-connecting pipes, and of a system of valves, all of the valves in the branch pipes normally being closed. Thus, when the first tank 35 81 is emptied, valve 94 in its lead-in pipe 89 is closed, and valve 95 in pipe 86 between tank 81 and the juncture of pipes 86 and 91 is also closed. This cuts out tank 81. Valve 96 in pipe 91 is then 40 opened to permit the pressure fluid to enter the top of the second tank through pipe 86. When this tank is emptied valve 97 in pipe 87 is closed, valve 96 is closed, and valve 98 in pipe 91 is opened. This procedure is followed as each successive tank is emptied.

45 As a result of cutting empty tanks out of the pressure line it will be seen that the area of preservative solution to which the steam is applied is never greater than the interior area of a single tank 81. Consequently, the rate of steam condensation is considerably less than it would be if the large pressure measuring tank 3 were used. Also, due to the smaller volume of each tank 81, the differences in temperature of the preservative and tank between the upper and lower portions 50 are not so great, thus reducing strain on the tank.

55 Another, but more undesirable arrangement of tanks 81 is made by connecting them in parallel instead of in series.

According to the provisions of the patent statutes, I have explained the principle and mode of operation of my invention and have illustrated and described what I now consider to represent its best embodiment. However, I desire to have it understood that, within the scope of the appended claims, the invention may be practiced otherwise than as specifically illustrated and described.

I claim:

1. The combination in wood-treating apparatus comprising a treating cylinder, a storage and working tank, a conduit connecting the bottom of the storage tank to the bottom of the treating cylinder, an ejector connected to the

top of the treating cylinder, and a conduit connecting a source of fluid pressure to the ejector for evacuating the treating cylinder, of a plurality of relatively small pressure measuring tanks, conduits serially connecting said pressure measuring tanks end to end, a conduit connecting said source of fluid pressure and the tops of the pressure measuring tanks, a conduit leading from the bottom of the last pressure measuring tank in line to the treating cylinder, and valves 10 arranged for cutting out each successive pressure measuring tank as it is emptied.

2. The combination in wood-treating apparatus comprising a source of fluid under pressure, a treating cylinder, a storage and working 15 tank, a conduit connecting the storage tank to the treating cylinder, and means for evacuating the treating cylinder, of a plurality of relatively small pressure measuring tanks, a conduit connecting said source of fluid pressure to one end 20 of each of the pressure measuring tanks, a conduit connecting the other end of each of the pressure measuring tanks to the treating cylinder, and valves arranged for admitting fluid pressure from said source to one pressure measuring tank 25 at a time and for cutting that tank out of line when it is emptied.

3. The combination in wood-treating apparatus comprising a source of fluid under pressure, a treating cylinder, a storage and working 30 tank, a conduit connecting the storage tank to the treating cylinder, of a plurality of relatively small pressure measuring tanks, conduits serially connecting said pressure measuring tanks end to end, a conduit connecting said source of 35 fluid pressure and the tops of the pressure measuring tanks, a conduit leading from the bottom of the last pressure measuring tank in line to the treating cylinder, and valves arranged for cutting out each successive pressure measuring tank 40 as it is emptied.

4. The combination in wood-treating apparatus comprising a treating cylinder, a storage and working tank, a conduit connecting the bottom of the 45 treating cylinder, an ejector connected to the top of the treating cylinder, and a conduit connecting a source of steam pressure to the ejector for evacuating the treating cylinder, of a plurality of relatively small pressure measuring tanks, conduits serially connecting said pressure measuring tanks end-to-end, a conduit connecting said source of steam pressure and the tops of the pressure measuring tanks, a conduit leading from the bottom of the last pressure measuring tank in line to the treating cylinder, and valves arranged for cutting out each successive 50 pressure measuring tank as it is emptied.

5. The combination in wood-treating apparatus comprising a source of steam pressure, a 60 treating cylinder, a storage and working tank, and a conduit connecting the storage tank to the treating cylinder, of a plurality of relatively small pressure measuring tanks, conduits serially connecting said pressure measuring tanks 65 end-to-end, a conduit connecting said source of steam pressure and the tops of the pressure measuring tanks, a conduit leading from the bottom of the last pressure measuring tank in line to the treating cylinder, and valves arranged for cutting out each successive pressure measuring tank as it is emptied.

GRANT B. SHIPLEY.
